ILLUMINATED GLOBE MOUNTING

Raymond R. Dupler, Toledo, Ohio

Application March 17, 1948, Serial No. 15,453

3 Claims. (Cl. 35—46)

1

This invention relates to illuminated globes and particularly to the construction of geographical or terrestrial globes and the mounting means therefor.

There are a number of factors that must be taken into consideration in the construction of an illuminated globe. One of these relates to the limitations on the globe member itself with respect to its size. For example, when it is desired to manufacture a large size globe, say greater than twelve inches in diameter, it is difficult to fabricate the globe in one piece of light penetrable material without resorting to the use of such a large opening as will render the subsequent mounting more difficult and insecure. For such purposes, it is more expedient to manufacture the globe member of two hemispherical sections in which the openings for mounting purposes may be obtained within specifications without limitation as to the size of the hemispherical sections. However, in so doing, other problems arise with respect to the joinder and mounting of the hemispherical sections.

A primary object of this invention is to produce an internally illuminated globe formed of two hemispherical sections including means for holding the two hemispherical sections together in the desired relation and other means rotatably and removably mounting the assembled globe in a support.

A further object is to produce a globe of two hemispherical sections and a mounting means therefor including a substantially rigid support extending through the interior of the globe for holding the hemispherical sections together, means for preventing relative rotational and horizontal movement between the globe sections, and other means cooperating with the globe whereby the globe may be rotatably and detachably arranged in a globe encircling support.

A further object is to provide an illuminating means that cooperates with the mounting means in a manner to enable the light source and connecting means to be moved into or out of the globe as a unit without disturbing the globe assembly.

Further objects and advantages will herein-after become apparent from the ensuing description during the course of which reference is had to the accompanying drawings in which

Figure 1 is a side elevational view of a terrestrial globe with portions broken away to illustrate the features of the invention;

Figure 2 is a sectional view taken along the line 2—2 of Figure 1;

Figure 3 is a sectional elevational view taken along the line 3—3 of Figure 1;

Figure 4 is a sectional view taken along the line 4—4 of Figure 1; and

2

Figure 5 is a perspective view of a connector for the hemispherical sections.

Referring now to the drawings, it may be seen that a geographical globe 10 is rotatably mounted in a meridian ring 11 formed of metal or other rigid material. Although the support for the meridian ring forms no part of the present invention, it is to be understood that the ring may be mounted on rollers and guided for circumferential movement by a support, or it may be stationarily mounted on a support, as illustrated in my copending application Serial No. 622,144, filed October 13, 1945, now Patent No. 2,511,770 and entitled "Globe Mounting." For the purpose of mounting the globe in the desired relation, a recess 12 is provided in an inner wall portion of the ring 11 and diametrically opposed thereto, a groove 13 extends transversely across the greater portion of the inner wall of the ring. A set screw 14, having a threaded end portion capable of extending into the groove when properly inserted through a radial opening 15 in the ring, locks the globe mounting means in position as will hereinafter be described.

The globe itself consists of two hemispherical shells or sections 16 and 17 formed of glass, plastics or any other translucent, substantially rigid material, each section having an opening 18 and 19 respectively of specified dimension formed in the base thereof. The desired map or terrestrial design may be placed on the outer wall of the globe before or after the sections are assembled, but if it is desired to place the figurations on the inner wall of the globe, the positioning thereof must be effected before the sections are assembled. Very pleasing effects are produced by mounting the maps on the inner wall of the globe.

One of the important features of this invention resides in the means for joining the hemispherical sections in a manner that will produce a satisfactory structure and prevent transverse or rotational movement of one hemispherical section relative to the other. Ordinarily, an adhesive is applied to the edges of the sections before they are brought together in abutting relation, but there are many instances where solely such means have been found to be insufficient for holding the parts together. For example, the adhesive is not always immediately effective, the abutting edges often do not make a perfect fit, or the adhesive becomes ineffective under certain conditions or aging.

I have found that the assembly can be greatly simplified and the joint improved if a series of mounting members 20 are placed at spaced-apart portions all around the meeting edge walls of the globe sections. These mounting members 20 are formed of substantially rectangular strips of sheet metal or plastic having a very thin wall,

in the order of 0.001 to 0.003 of an inch, although thicknesses up to 0.010 of an inch have successfully been used. Each mounting member is divided into a body portion 24 corresponding in width to the thickness of the hemispherical section walls and tabs 21, 22 and 23 extending laterally in each direction from the body portion by a series of lateral slits. More or less than three tabs may be formed and these may be bent so that they extend alternatively in opposite directions perpendicularly from the body portion to form oppositely facing channel sections for receiving the edge wall portions of each hemispherical section when brought into assembled relation. In this position, the tabs grip the respectively opposite faces of the section walls and prevent their relative rotational or horizontal movement from the assembled portion. For example, tabs 21 and 23 may be turned up to grip the walls of section 16 while tabs 22 may be turned down to grip the walls of section 17, thereafter to prevent inadvertent relative movement. Alternatively, the outwardly extending tabs may be bent after the sections 16 and 17 have been brought together in their assembled relation.

It is within the concept of this invention to form the mounting members of transparent material, whereby their presence is relatively unnoticed. This is of special significance when the map is mounted on the inner wall of the globe, and an unobstructed view through the globe is desired. If greater rigidity is desired, the engaging surfaces of the mounting member 20 may be provided with adhesive material prior to engagement with the section walls, and if desired, the edge portion of each hemispherical section where the mounting members are to be placed, may be grooved to compensate for the thickness of the body portion disposed therebetween in the assembled relation.

The hemispheres are also held together in their assembled relation by a rigid support 30 extending substantially diametrically through the interior of the globe, where it also functions as the axis of the globe. This internal support is a cage-like structure which, as illustrated in Figures 1 and 2, is formed of four metallic rods *a*, *b*, *c* and *d*, which are centrally outwardly bowed and connected at their lower ends to the upper edge of a sleeve 31. The sleeve 31 is formed of a diameter corresponding substantially to the size of the opening 18 through the south pole portion of the lower hemispherical section 17, and it has an outwardly turned flange 32 integral with its lower end. The flange preferably is separated from the inner wall of the section 17 adjacent the opening, by a gasket 33. The gasket operates principally as a pad or cushion and to prevent relative movement between the sleeve and the globe. As such it may be formed of felt, cork, rubber-like materials or other resilient frictional generating substances.

Fitting through the opening 18 and telescoping the sleeve 31 is a bushing in the form of a sleeve 34, having an outwardly extending flange 35 at the lower end thereof which is separated from the outer wall of the section 17 by another gasket 36. In the assembled relation, a portion 37 of the inner sleeve 34 is adapted to extend beyond the outer sleeve 31, which portion is axially slit so that in the final assembly, the split sections or tabs 38 may be turned down over the outer sleeve, as illustrated in Figure 2, to secure the lower end of the cage in position. In this

position, the bushing and the sleeve 31 are combined with the flanged portions engaging the opposite faces of the hemispherical section adjacent the opening therebetween.

The opposite ends of the rod-like members *a*, *b*, *c* and *d* are fixed, as by welding, to the shank 39 of a screw-threaded rod 40 that operates as a bearing post having a rounded knob 41 at its upper end adapted rotatably to fit in the recess 12. The rod extends through the opening 19 and is adjustably locked in position relative thereto by a pair of cooperating nut members 42 and 43, one, 42, of which is disposed inside of the globe and the other outside of the globe. The nut member 42 threadably engages the rod 40 and has an upper curvilinear surface corresponding to the contour of the inner wall of the globe and a chamfered central portion 44 corresponding dimensionally and in registry with the opening 19 through the hemispherical section 16. Two or more notches 45 lead from the chamfered section to provide means by which the nut may be turned, as by a suitable tool, from the outside of the globe. Another nut 43 threadably engaging the rod outwardly of the nut 42, has a curvilinear inner wall corresponding to the contour of the outer wall of the globe, and is provided with a boss 46 which fits through the opening 19 and nests with the chamfered portion 44. These nut members cooperate to grip the opposite walls of the globe and secure the cage-like support 30 in a manner tensionally to hold the hemispherical sections together.

In actual practice, the globe is assembled before being mounted in the meridian ring. The following suggests a suitable chronological order of steps that may be followed in the assembly. The bushing 34 is inserted through the south pole opening 18, and then the sleeve 31 secured to the lower ends of the rods *a*, *b*, *c* and *d* is telescoped over the sleeve 34 until the flange 32 comes to rest against the gasket 33 and the inner wall of the section 17. The tabs 38 are turned down over the sleeve 31 to lock the described elements in position.

Then, in order to insure full engagement between the two hemispherical sections, the nut 42 is turned down to a position below that which it is to assume in the final assembly. The mounting members 20 are properly positioned on the edge of one hemispherical section and at the same time, adhesives may be applied to the surfaces. Then the other hemispherical section is lowered onto the first so that its edge portion seats in the upturned channels of the mounting members and the edges substantially meet all around to form the globe. If the outer tabs have not previously been turned, it may be accomplished at the present time. A tool is inserted through the opening 19 for turning up the nut 42 until it firmly engages the under side of the upper section 16, and then the nut 45 is turned down accurately to center the globe relative to the rod 40 which forms a part of the axis structure and cooperates with the nut 42, firmly to grip the globe therebetween. For purposes of reducing the tendency of the globe to move relative to the nut members and to provide for resilient engagement, gaskets 47 and 48 are interposed between the nut surfaces and the adjacent globe bodies.

The mounting for the illuminating source also operates rotatably to secure the globe in the meridian ring. The mounting bracket comprises a

rigid disc member 50 adapted, with a minimum of friction, slidably to engage the under side of the flange 35 and having a central cylindrical section or block 51 that telescopes a short distance into the sleeve 34. A nipple 52, threadably secured to the section 51, extends into the globe and mounts a socket 53 for the illuminating bulb 54. The electrical cord 55 for the socket passes through the nipple 52 and through openings 56 and 57 to the current source. For mounting the bracket in a manner to prevent relative rotational movement, a boss 60, having a threaded opening on its under side, depends from the bracket and seats in the groove 13, in which position it is locked by the set screw 14 engageable therewith.

The operation of the globe will be evident from the description and drawings. Suffice it to say that the globe turns relative to the meridian ring while being supported on the mounting bracket. The globe may be dismounted merely by loosening the set screw 14 and sliding the globe with the mounting bracket sidewise until the meridian ring is cleared. If it is desired to remove the entire globe, the assembly may then be lowered until the knob 41 clears the recess 12, or if it is only desired to remove or replace the illuminating bulb, the bracket may be removed as a unit with the globe and attachments for replacement or repair.

From the description, it will become evident that I have invented a new and improved illuminated globe assembly having simple and novel means for mounting and maintaining the hemispherical sections, from which the larger sized globes are manufactured, in their assembled relation and for removably mounting the assembled globe in an arcuate support by means of a mounting bracket that also forms a part of the lighting fixture. For purposes of effecting the desired assembly and mounting, relatively few and simple parts are employed thereby to enable a globe, having illuminating features, to be manufactured in any size at a relatively low cost, and to enable replacement of parts or repair without difficulty or particular shells.

It is to be understood that numerous changes in the details of construction, arrangement and operation may be effected without departing from the spirit of the invention especially as defined in the appended claims.

What I claim is:

1. An illuminated globe comprising a pair of hemispherical shells, each having an aperture in a position to be diametrically opposed when the sections are together in the form of a globe, a bearing post, means adjustably mounting said bearing post in one of said apertures, said mounting means comprising a pair of nuts threadedly engaging the bearing post, one nut being disposed within the globe and having a centrally recessed portion corresponding in size to that of the opening through the hemispherical shell, notches in said nut for enabling turning movement to be effected from without the globe, the other nut being disposed outside of the hemispherical shell, a central post on said latter nut extending through said opening and fitting within said depressed portion in the assembled relation, outwardly flared portions on said nuts for gripping the adjacent hemispherical shell wall therebetween when in assembled relation, bushing means stationarily mounted in the other aperture, an internal support connecting said bushing means with said bearing post for holding said hemi-

spherical shells together, an arcuate mounting for the globe having a notch for receiving said bearing post, a combined lamp socket and bushing engaging support for mounting said lamp socket internally of the globe and rotatably supporting the latter, and means for detachably securing said support to said mounting.

2. An illuminated globe comprising a pair of hemispherical shells each having an aperture in position to be diametrically opposed when the sections are together in the form of a globe, a bearing post, means for adjustably mounting said bearing post in one of said apertures, a sleeve corresponding diametrically to the opening through the hemispherical shell, an annular flange on the sleeve adapted to seat against one wall portion adjacent the opening, another sleeve telescoping within said first sleeve, an annular flange on said latter sleeve for engaging the opposite wall portion adjacent the opening, means for locking the sleeves in their telescoped position thereby to grip the hemispherical shell therebetween, an internal support connecting one of said sleeves with said bearing post for holding the hemispherical shells together, an arcuate mounting having a notch for receiving said bearing post, a combined lamp socket and bushing engaging support for mounting said lamp socket internally of said globe and rotationally supporting the latter, and means for detachably securing said support to said mounting.

3. An illuminating globe comprising a pair of hemispherical shells each having an aperture in position to be diametrically opposed when the sections are together in the form of a globe, a bearing post, means for adjustably mounting said bearing post in one of said apertures, a sleeve corresponding diametrically to the opening through the hemispherical shell, an annular flange on the sleeve adapted to seat against one wall portion adjacent the opening, another sleeve telescoping within said first sleeve, an annular flange on said latter sleeve for engaging the opposite wall portion adjacent the opening, means for locking the sleeves in their telescoped position thereby to grip the hemispherical shell therebetween, an internal support connecting one of said sleeves with said bearing post for holding the hemispherical shells together, an arcuate mounting having a notch for receiving said bearing post, a combined lamp socket and bushing engaging support for mounting said lamp socket internally of said globe and rotationally supporting the latter, a boss depending from said support, said arcuate mounting having a slot extending laterally from one side wall for receiving said boss, and said screw means extending through the under side of said arcuate mounting and operatively engaging said boss for holding same in assembled position.
